WHEEL ASSEMBLY FOR TRAILERS

Leroy G. Houger, Star Route, Box 7,
Prescott, Wash. 99348

Filed Mar. 4, 1970, Ser. No. 21,726

Term of patent 14 years

Int. Cl. D12—16

U.S. Cl. D14—3

FIG. 1 is a left front perspective view of the wheel assembly for trailers embodying my new design showing to advantage the rotatable wheel support in a normal up position and the hitch of this invention carried by a hitching support assembly mounted on a commonly known trailer which is shown in broken lines for illustrative purposes;

FIG. 2 is a right front perspective view showing to advantage the rotatable wheel support in a down position and the hitch of this invention carried by a hitching assembly mounted on a commonly known trailer frame which is shown in broken lines for illustrative purposes; and

FIG. 3 is a right front perspective view as viewed from the side opposite FIG. 1 showing to advantage the rotatable wheel support in a normal up position and the hitch of this invention carried by a hitching support assembly mounted on a commonly known trailer frame which is shown in broken lines for illustrative purposes.

I claim:

The ornamental design for a wheel assembly for trailers, substantially as shown and described.
